JOSEPH P. LAMBERT, OF NEW YORK, N. Y.

BILLIARD-BALL.

1,286,657.

Specification of Letters Patent.

Patented Dec. 3, 1918.

Application filed September 11, 1917. Serial No. 190,781.

To all whom it may concern:

Be it known that I, JOSEPH P. LAMBERT, a subject of the King of Great Britain, and a resident of the city of New York, borough 5 of Manhattan, in the county and State of New York, have invented a new and Improved Billiard-Ball, of which the following is a full, clear, and exact description.

Among the principal objects which the 10 present invention has in view are: to add a feature of chance to games played with billiard balls; to provide means for scoring independently of the rolling of the billiard balls; to permit a chance score and a skill 15 score being made in games employing billiard balls; and to avoid unnecessary interference with the playing of the conventional games wherein billiard balls are used.

Drawings.

Figure 1 is a perspective view of a billiard ball constructed and arranged in accordance with the present invention;

Fig. 2 is a section thereof, the section being taken as on the line 2—2 in Fig. 1.

Description.

The game for the playing of which the present ball is especially designed, is one 30 where an "honor" score or a score depending on chance, is made at the same time that the usual score depending on skill is accounted for. The "honor" or chance score is dependent on the rolling or settling of what is 35 known as the object ball, which is employed in the three-ball game of billiards. The object ball is usually colored to distinguish it from the two cue balls.

When constructed and arranged in accordance 40 with the present invention, a series of spots 7, or level areas, is formed on the surface of the ball. The spots are disposed in paired relation, the members of each pair being at the extremes of a diameter of the ball. Usually some symbol, and preferably 45 a numeral, is disposed on all of the spots 7, the symbol on each spot being independent

of the symbols on the other spots. As a result of this arrangement, when the ball settles on any one of the spots 7, the opposite 50 spot of the pair to which it belongs, is viewed from above and this is used as the particular counter.

When playing a game using the ball having the symbol spots 7, after each shot, the 55 player examines the said ball to ascertain the symbol which is exposed at the top of the ball. This symbol is added to the score with which the player is credited.

It is obvious that the rules of the game 60 may be infinitely varied and the count of the "honor" score as ascertained by the symbol, may be dependent upon the success of the shot or score of the regular game whatever that may be. In other words, the rules may 65 provide that the score of the "honor" shall depend upon the success or failure of the billiard shot with which the object ball is moved.

A further feature of chance is added to 70 the game by the fact that the spots 7 being relatively small in area to avoid interfering as much as possible with the roll of the object ball, the possibility of the said object ball settling upon a spot is somewhat reduced. It will be understood, of course, that in the event of the ball not so settling upon 75 one of the spots, the "honor" count would not be allowed.

It will be understood that the spots 7 may 80 be produced on the object ball by grinding or other well-known and approved means.

Claim.

A rolling ball as characterized having a 85 plurality of flat settling spots formed in the surface thereof, said spots being widely separated and disposed in paired relation, the members of each pair being disposed at the extremities of the same axis, said spots being 90 provided with game counter symbols, the symbol on each spot being different from all other symbols.

JOSEPH P. LAMBERT.
